UNITED STATES PATENT OFFICE.

JOHN MAGEE, OF CHELSEA, MASSACHUSETTS, ASSIGNOR TO THE MAGEE FURNACE COMPANY.

DESIGN FOR HEATING-STOVES.

Specification forming part of Design No. 6,079, dated November 4, 1873; application filed July 29, 1873.
[Term of Patent 7 years.]

To all whom it may concern:

Be it known that I, JOHN MAGEE, of Chelsea, in the county of Suffolk and State of Massachusetts, have invented and produced a new and original Design for a Stove, of which the following is a full, clear, and exact description, reference being had to the accompanying drawing, making part of this specification.

This invention consists in an ornamental design for the base of a stove, and also in the design for the frame of the door through which the fuel is introduced.

In the drawing, A represents the upper or main portion of the stove, which is of oval form in cross-section, and rests upon the base B, at each corner of which are three columns or pillars, b. On the sides of the base B, between the pillars b of two contiguous corners, is a representation, c, of one or more figures in bass-relief; but, if preferred, these representations may be omitted, and the sides of the base left plain. C is the door, through the opening controlled, by which the fuel is introduced into the stove, and D is the frame to which the door is pivoted. At each side of the frame D is a column or pillar, d, the top of the frame being surmounted by ornamental scroll-work, e, the style or design of this door-frame being intended to correspond with that of the base B.

What I claim as my invention, and desire to secure by Letters Patent, is—

1. The design for the base B of an oval-shaped or cylindrical stove, consisting essentially of the pillars b at its corners, substantially as herein shown and described.

2. The design for the door-frame D of a stove, consisting of the pillar d at each side, substantially as herein shown and described.

Witness my hand this 23d day of July, A. D. 1873.

JOHN MAGEE.
